FOLDABLE BUCKSAW AND CASE THEREFOR

Edwin R. Kilmer, Johnstown, N. Y.

Application April 29, 1952, Serial No. 285,004

1 Claim. (Cl. 145—32)

2

1 This invention relates to bucksaws and more particularly to a foldable bucksaw especially useful in camping and similar activities, and a carrying case for carrying the saw when in folded condition.

It is among the objects of the invention to provide an improved foldable bucksaw which can be folded to a compact condition and placed in a carrying case or bag for convenient transportation and storage; in which the frame of the saw completely encloses and protects the saw blade when the saw is in folded condition; which can be quickly and easily unfolded and conditioned for use; and which is simple and durable in construction, economical to manufacture, convenient and effective in use, and neat and attractive in appearance.

Other objects and advantages will become apparent from a consideration of the following description and the appended claims in conjunction with the accompanying drawing wherein:

Figure 1 is a side elevational view of a bucksaw illustrative of the invention when the saw is in condition for use;

Figure 2 is a side elevational view of a portion of the saw in partly folded condition;

Figure 3 is an edge elevational view of a compression bar constituting an operative component of the saw;

Figure 4 is a side elevational view of the portions of the saw illustrated in Figure 2 when in completely folded condition;

Figure 5 is a transverse cross sectional view on the line 5—5 of Figure 4; and

Figure 6 is a perspective view of a carrying case for the saw when in folded condition.

With continued reference to the drawing, the saw comprises, in general, a frame 10 and a blade 11.

The frame 10 comprises substantially straight, 40 elongated end members 12 and 13 each having a longitudinally extending groove, as indicated at 14 and 15 respectively, in one edge thereof, a tension linkage 16 connected between the end members 12 and 13 at corresponding ends of the latter, and a compression bar 17 extending between the end members intermediate the length thereof and substantially parallel to the tension linkage 16. The saw blade 11 has saw teeth 18 along one edge thereof and is pivotally connected at its respectively opposite ends to the frame end members 12 and 13 at the ends of these end members remote from the tension linkage 16, as indicated at 19 and 20.

The tension linkage 16 includes a link 21 piv-

totally connected at one end to the frame end member 12 by a ring bolt and eye connection 22, a turnbuckle 23 pivotally connected at one end to the other end of the link 21 by an eye connection 24, a link 25 connected at one end to the other end of the turnbuckle by an eye connection 26 and detachably connected at its other end to the frame end member 13 by means including a hook and eye connection 27. When the frame end members 12 and 13 are disposed in spaced apart and substantially coterminous relationship with the compression bar 17 extending therebetween and the tension linkage 16 connected between the ends of the frame members 10 remote from the saw blade 11, tightening the turnbuckle 23 will place the saw blade 11 under tension in a manner well known to the art.

When the saw is in its operative condition, as illustrated in Figure 1, the groove 14 in the end member 12 is disposed in the inner edge of this end member and the groove 15 in the end member 13 is disposed in the outer edge of the corresponding end member.

The compression bar 17 has plates or ears 28 and 29 secured to one end thereof and disposed one at each side of the bar and projecting outwardly from the adjacent end of the latter and similar plates 30 and 31 secured thereto at its opposite end, one on each side of the bar and projecting outwardly from the corresponding end of the bar. These plates are notched in their outer ends, as indicated at 32 and 33 in Figure 1, and the frame end members 12 and 13 are provided with pins 34 and 35 respectively, extending transversely therethrough and projecting from the opposite sides thereof intermediate the length of the end members. The pins 34 and 35 are seated in the notches 32 and 33 in the compression bar end plates when the bar is in position, as illustrated in Figure 1, and retain the bar in proper position relative to the end members. The bar is removable from the end members by simply moving the end members away from the corresponding ends of the bar when the tension linkage 16 has been loosened.

In order to fold the saw, the turnbuckle 23 is first loosened and the hook and eye connection 27 separated to release the tension linkage 16 from the end member 13 of the saw frame. The end members 12 and 13 are then moved apart and the compression bar 17 removed from the frame. The blade 11 is then swung relative to the end member 12 about the pivotal connection 19 until the back side of the blade is received in the groove 14 in the inner side of the end mem-

ber 12. The end member 13 is then swung around its pivotal connection 20 with the blade until the toothed edge of the blade is received in the groove 15 in the end member 13, as shown in Figures 2 and 4 of the drawing. When the end members 12 and 13 are moved together until their grooved edges are in contact, the saw is completely enclosed in the grooves 14 and 15, as shown in Figures 4 and 5. After the end members 12 and 13 and the saw blade 11 have been folded together to the condition illustrated in Figure 4, the tension linkage 16 and the compression bar 17 are positioned alongside the end members and the assembly is inserted in the carrying case, generally indicated at 31 and illustrated in Figure 6.

The carrying case or bag 31 is an elongated receptacle of rectangular cross sectional shape formed of a suitable material, such as heavy canvas, and has one end arcuately curved convexly and provided with a slide fastener 38. A carrying handle 39 is attached to the case at one edge thereof for convenience in carrying the case with the folded saw disposed therein.

When the saw is folded and placed in the case, it can be conveniently carried in a vehicle, such as an automobile, canoe or boat, or even on a back-pack, if desired, as the saw may be made of small size and light weight, and the saw can be quickly removed from the carrying case and assembled in its operative condition for use, when desired.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A foldable saw assembly comprising an elongated compression bar, elongated end members disposed one at each end of said compression bar and each detachably connected intermediate its length of said compression bar, a saw blade disposed between said end members substantially parallel to said compression bar and pivotally connected at its respectively opposite ends to the corresponding ends of said end members, and an adjustable length tension linkage disposed between said end members at the side of said compression bar remote from said saw blade and having one end pivotally connected to the end of one of said end members remote from said blade and having the other end detachably connected to the end of the other of said end members remote from said blade, said end members and said saw blade being of substantially the same length and said end members having longitudinally extending grooves therein receiving said saw blade when said end members are disconnected from said compression bar and said tension linkage and folded relative to said blade about the connections between said end members and said saw blade, one of said end members having its blade receiving groove in the edge thereof nearest the adjacent end of said compression bar and the other of said end members having its blade receiving groove in the edge thereof remote from the adjacent end of said compression bar and each of said grooves having a depth substantially equal to one half the width of said saw blade.

gated compression bar, elongated end members disposed one at each end of said compression bar and each detachably connected intermediate its length of said compression bar, a saw blade disposed between said end members substantially parallel to said compression bar and pivotally connected at its respectively opposite ends to the corresponding ends of said end members, and an adjustable length tension linkage disposed between said end members at the side of said compression bar remote from said saw blade and having one end pivotally connected to the end of one of said end members remote from said blade and having the other end detachably connected to the end of the other of said end members remote from said blade, said end members and said saw blade being of substantially the same length and said end members having longitudinally extending grooves therein receiving said saw blade when said end members are disconnected from said compression bar and said tension linkage and folded relative to said blade about the connections between said end members and said saw blade, one of said end members having its blade receiving groove in the edge thereof nearest the adjacent end of said compression bar and the other of said end members having its blade receiving groove in the edge thereof remote from the adjacent end of said compression bar and each of said grooves having a depth substantially equal to one half the width of said saw blade.

EDWIN R. KILMER.
